UNITED STATES PATENT OFFICE.

CHARLES W. LENT, OF TINGLEY, IOWA.

DOOR-SECURER.

945,558.

Specification of Letters Patent.

Patented Jan. 4, 1910.

Application filed September 30, 1909. Serial No. 520,294.

To all whom it may concern:

Be it known that I, CHARLES W. LENT, a citizen of the United States, and a resident of Tingley, in the county of Ringgold and State of Iowa, have invented a certain new and useful Door-Securer, of which the following is a full, clear, and exact description.

My invention relates to securers for doors, windows and the like, and provides a se-
10 curer adapted to be quickly applied to closures, for holding the same in a locked position.

My invention is more particularly adapted for securely locking doors, and embodies two
15 plates movable relative to each other, one of the plates being provided for insertion between a closure member and the frame thereof, and equipped with suitable gripping means for holding the same in place, while
20 the other plate is adapted to be engaged by the first-named plate by means of a lug on the second-named plate engaged by a locking means on the first-named plate, the second-named plate having a stop flange there-
25 on adapted to engage the said closure and securely hold the same in locked position.

My invention further embodies novel fea-
30 tures of construction as will be hereinafter more fully described and particularly set
forth in the appended claim.

Reference is to be had to the accompany-
35 ing drawings forming a part of this specifi-
cation, in which similar characters of refer-
ence denote corresponding parts in all the
views, and in which—

Figure 1 is a fragmentary sectional plan view of a door and the frame thereof and showing my invention attached to the frame and in the initial position for securing the
40 door. Fig. 2 is a fragmentary sectional plan view of a door and the frame thereof, showing my invention attached to the same and engaging the door to hold the same in locked position. Fig. 3 is a perspective of one of
45 the plates partially comprising my inven-
tion. Fig. 4 is a perspective of a second plate partially comprising my invention. Fig. 5 is a side view of the screw bolt adapt-
50 ed to hingeably secure the two plates em-
bodied in my invention.

My door securer comprises a gripping plate 1 having at one end thereof projecting pointed lugs 2. The other end of the grip-
55 ping plate 1 is turned inwardly so as to form a bearing 3 for a screw bolt 4 which passes

therethrough and hingedly secures the plate 1 to a second plate 5. A hole 6 is provided in the plate 1, and adjacent thereto a cam 7 having a handle 7^a is pivoted to the plate by means of a pin 8. The second plate 5 hinged to the plate 1 by means of the screw bolt 4 passed through bearings 9 and 10 in the plate 5, and the bearing 3 on the plate 1, is provided with a lug 11 and a stop flange 12 as will be clearly seen by referring to Fig. 3. 65

When it is desired to apply the door se-
curer for locking a door 13 hinged to a
frame 14 at 15 and provided with suitable
knobs 16, the gripping plate is placed against
the door-jamb 17 with the gripping lugs 2 70
pressed into the door-jamb 17 to hold the
plate 1 in position. The door 13 is then
closed. This forces the lugs 2 still deeper
into the door-jamb 17. Then the plate 5
hinged to the plate 1 is swung around so that 75
it engages the plate 1, the lug 11 on the plate
5 passing through the opening 6, and the
stop flange 12 engaging the door 13, as will
be clearly seen by referring to Fig. 2. The
cam 7 is then manipulated so as to engage 80
the lug 11, as will also be seen by referring
to Fig. 2. The door is now securely held in
a locked position and can only be opened by
disengaging the cam 7 and the lug 11 and
swinging the plate 5 outwardly, away from 85
the plate 1. The hinge member 3 is prefer-
ably elongated to permit of the screw bolt 4
secured to the locking plate 5, by bearings 9
and 10, to move or slide longitudinally of
the plate 1, as well as being hingedly secured 90
to the said plate.

When it is desired to repeatedly use the
door securer on the same door, a rectangular
plate 18, having an elongated slot therein
is provided, to be secured in the door jamb. 95
Then when the securer is applied the holes
first made by the gripping points 2 can be
easily located and used again, thereby obvi-
ating the necessity of making new holes for
the gripping points 2. 100

It will be understood that although I have
described my door securer as applied to a
door, it can be conveniently used for various
closures such as windows, cabinets and the
like. 105

Having thus described my invention I
claim as new and desire to secure by Letters
Patent:

A door securer comprising a gripping
plate for insertion between a closure and the 110

frame thereof, gripping means integral with the said plate for holding the same in position, and a locking plate mounted to turn and to slide on the said gripping plate, a hook-shaped lug on the said locking plate engaging the gripping plate, a cam on the said gripping plate engaging the said hook-shaped lug and securely holding the same, and means on the said locking plate engag-

ing the said closure for securely holding the same in a locked position.

In testimony whereof I have signed my name to this specification in the presence of two subscribing witnesses.

CHARLES W. LENT
